Patented Aug. 9, 1921.

FIG. 1

FIG. 2

INVENTOR
P. X. Trudel
BY E. J. Fatherstonhaugh
ATTORNEY

UNITED STATES PATENT OFFICE.

FRANCOIS XAVIER TRUDEL, OF SHAWINIGAN FALLS, QUEBEC, CANADA.

GRINDSTONE-MOUNTING.

1,386,743.

Specification of Letters Patent. Patented Aug. 9, 1921.

Application filed December 20, 1920. Serial No. 432,129.

To all whom it may concern:

Be it known that I, FRANCOIS XAVIER TRUDEL, residing at Shawinigan Falls, in the county of St. Maurice, in the Province 5 of Quebec, in the Dominion of Canada, have invented a new and useful Grindstone-Mounting, of which the following is the specification.

The invention relates to grindstone mounting, as described in the present specification and illustrated in the accompanying drawings that form part of the same.

The invention consists essentially in the novel means employed for reinforcing the 15 stone from its axis.

The objects of the invention are to avoid the dangers to life and property through the bursting of stones; to facilitate the operation of grinding by the precision in the 20 setting to position and maintaining that position; and generally to provide a grindstone equipment for wood pulp and other uses that will prove efficient, durable and serviceable.

25 In the drawings, Figure 1 is a vertical and cross-sectional view of the stone as mounted according to this invention.

Fig. 2 is a side elevation showing a side 30 mounting plate broken away to disclose a reinforcing groove and feed trough.

Like numerals of reference indicate corresponding parts in each figure.

Referring to the drawings, the stone 1 is formed in cylindrical shape having the circumferential grinding surface 2 and the central shaft orifice 3.

The annular recesses 4 are formed in the sides of the stone 1 and surround the shaft orifice 3, said recesses having beveled side 40 walls 5 extending from the bed 6 to the face of the stone at each side.

The radial grooves 7 lead to the recesses 4 and are made in the side faces of the stone and form feed troughs.

45 The side plates 8 or flanges are formed with the inwardly projecting hubs 9 and the reinforcing ribs 10 and are screw-threaded on to the shaft 11, which is a little heavier where it passes through the stone though of lesser diameter than the central shaft orifice 3.

The mounting of the stone 1 is accomplished by first filling in the space 12 between the shaft and stone with a packing 13, either 55 wet or dry, of cotton waste, sulfite pulp or other suitable material.

The space 12 may be entirely or partly filled up by the said packing; of course, it is necessary to hold the stone in a central position in relation to the shaft during this filling process and this is done by wedges or holders not shown, but used in common practice.

The side plates or flanges are screwed up to position in order to assure the proper setting of the stone previous to the filling of the space 12, but removed for filling purposes. After filling, the side plates or flanges are again screwed close to the stone, but not quite home. The stone and edges of side 70 plates are then plastered with mud or other substance to close the cracks between plates and stones leaving the entrances to the feed troughs open.

A semi-liquid solution is poured into 75 grooves or feed troughs 7 and this flows into the recesses 4 around and about the hubs 9 and into the space 12 as far as the filling 13 at each end, and if necessary, tamped to insure the complete filling of the spaces. 80

This solution is made up of cement and water or other substance that will reach a consistent or hard solid state, and it will be seen that it forms a solid mass completely around the shaft at each end of said stone 85 with the projecting ribs 14 of cement filling the grooves 7. The side plates or flanges 8 are screwed home after the solution has been introduced and the iron is hammered until a good close fit is secured. 90

What I claim is:

1. In a grindstone mounting, a grindstone having a central shaft orifice terminating at each end in an annular recess communicating with a groove or feed trough in the 95 stone, and extending toward the outer grinding surface, a shaft of lesser diameter than said orifice, closures on said shaft for said orifice, and filling surrounding said shaft and also occupying said recesses. 100

2. In a grindstone mounting, a shaft, a grindstone having a central shaft orifice of greater diameter than said shaft and recessed in the side faces around said orifice and outwardly from the recesses toward the edges, 105 side plates or flanges forming closures at the ends of said shaft orifice, a filling of a non-brittle nature in said orifice around said shaft and a hard resistant filling in said recesses. 110

3. In a grindstone mounting, a shaft having threaded portions forming the ends of

an enlarged part, a grindstone having a shaft orifice of greater diameter than said enlarged part and mounted thereon, and annular recesses around said orifice at the 5 ends having beveled side walls and registering with radial grooves in the side faces, a packing of compressible material surrounding said shaft within said shaft orifice, side

plates forming closures and having inwardly projecting and interiorly threaded hubs, and 10 a cementitious filling for said recesses extending inwardly thereinto from said radial grooves.

Signed at Montreal, Quebec, Canada, this 15th day of December, 1920.

FRANCOIS XAVIER TRUDEL.
